D. E. REED

TUB FOR CIDER PRESSES

Filed May 27, 1924

INVENTOR
Daniel E. Reed
BY
Charles S. Hensley
ATTORNEY

UNITED STATES PATENT OFFICE.

DANIEL E. REED, OF BROOKLYN, NEW YORK.

TUB FOR CIDER PRESSES.

Application filed May 27, 1924. Serial No. 716,102.

To all whom it may concern:

Be it known that I, DANIEL E. REED, a citizen of the United States, and a resident of the borough of Brooklyn, city and State 5 of New York, have invented certain new and useful Improvements in Tubs for Cider Presses, of which the following is a specification.

My invention relates to improvements in 10 tubs for cider presses. In cider presses it is customary to provide a tub of reticulated construction for holding the pomace while the juice is being forced out of it by pressure and the present invention relates to the 15 construction of the tub used for this purpose. One object of my invention is to provide a tub composed of hinged sections or halves connected together to hinge from one end of the tub with the axis of the hinge disposed transversely of the tub, whereby the 20 sections may be swung apart at the bottom to quickly release the charge of pressed pomace after the juice has been extracted. Where the tub is of solid construction, as in 25 former practice, it is difficult to dislodge the body of pomace after it has been subjected to the extreme pressures employed in extracting the juice, especially as there is a tendency for the pomace to be forced between the slats or bars of the tub. In the 30 present case the tub sections are adapted to swing outwardly at the bottom end which is sufficient to release the pomace because when the pressing operation has been completed the pomace will then lie in the lower 35 half of the tub and there is usually none at the top of the tub when the pressing operation is completed. The advantage in swinging the sections open at the bottom is that 40 the pomace is released more readily than if the sections were opened on a hinge line or axis extending vertically as has been proposed in other devices. Another object of my invention is to provide a simple and efficient clamp for drawing together and holding the bottom ends of the tub sections in 45 closed position during the pressing operation and which may be quickly opened notwithstanding the great pressure caused by 50 the pressing of the pomace into one end of the tub. The novel clamp is so constructed that it may be not only readily released but when it is closed the outward pressure of the pomace tightens the clamp and prevents it 55 from accidentally releasing the sections.

This clamp, while forming an important part of the full combination of my invention is also adapted to be used in various other relations where it is desired to draw two wires or straps toward each other. Other 60 advantages of the invention will be set forth in the following detailed description:

In the drawing forming part of this application,

Figure 1 is an elevation of a tub embodying 65 my invention and showing the same closed ready for pressing operation.

Figure 2 is an enlarged detail view of the hinge for holding the sections in pivotal relation,

Figure 3 is a plan view of one-half of the 70 tub, and

Figure 4 is an enlarged elevation of the clamp as applied to the tub.

Fig. 5 is a view taken on the line 5—5 75 of Fig. 4.

In the drawing I have shown a tub 1 adapted to rest upon a platform comprising strips 2 having open spaces between them through which the juice may fall into the 80 trough 3. The pomace is placed in the top of the tub and is compressed by a cap or head 4 which is forced down by the screws 5 which may be operated by hand or by power means. The tub comprises vertical 85 slats or bars 6 having spaces 7 between them through which the juice may be forced and these bars are connected near the top by means of a band or hoop formed in two sections. One section 8 passes around half the 90 tub and is suitably riveted or otherwise connected with half of the upright bars of the tub, and the other section 9 of the band passes around the other half of the tub and is riveted or otherwise bolted to the up- 95 right bars of this half of the tub the band being provided with handles 10 by which the tub may be bodily lifted. At opposite sides of the tub and where the separate halves join, the band members have upwardly extending projections 11 overlapping each other and through these there is a hinge pin 12 permanently attached. The two hinge pins 12 on opposite sides of the tub 100 determine the axis on which the tub sections pivot and it will be observed that this axial line is transverse of the tub so that when the two halves swing on the hinge they move outwardly or inwardly at their lower ends, the movement at the top of the sections 105 110

being relatively slight. Near the lower ends of the several bars 6 I provide a band or strap 14 which extends partly around the tub and it is also riveted to the bars 6 of the tub approximately half of its circumference and the free ends 15 of this section are separated slightly from the bars of the tub to provide space for the band section 16 which is riveted to the bars of the tub on one of the half sections thereof. There is a strap or band 17 having one end hooked or otherwise connected as shown at 18 with the free end 15 of the strap 14 and the other end of this section 17 is secured around a pin 19 carried by the clamp 20. There is another strap section 21 having one end 22 looped through or otherwise connected with one of the free ends of the strap 14 and the other end of the member 21 is looped around or otherwise connected with a fork shaped bar 23 which extends beyond and around the pin 19 when the parts are in the position indicated in the drawings, and the ends of this fork shaped member 23 are passed through the arms 24 of a yoke forming part of the clamp member.

The clamp consists of the yoke 24 extended to form a handle lever 25 which latter is concave in cross section in order that it may straddle the strap member 21 when the clamp is closed. The top and bottom of the fork arms 24 are turned at right angles to project toward the tub and the edges 26 of these projections are curved in order to have a rocking engagement with the fixed strap 16. These projecting members 27 also receive the pivot pin 19 as well as the ends of the fork-shaped member 23.

The device is shown in the closed position in the several figures, with the clamp closed to hold the lower ends of the tub in the closed position with the several bars of the tub extending vertically. In this condition the tub is adapted to receive a charge of pomace, either loose or preferably in a cloth sack, and after the pomace has been placed in the tub the head is forced down by the screw 5 to compress the pomace and extract the juice, which passes out between the bars of the tub and through the bars 2 of the platform on which the tub rests. The pressure exerted on the pomace by the head creates a strong outward pressure on the bars of the tub and as between the two halves of the tub the pressure is resisted at the top of the tub by the hinge connection and at the bottom of the tub it is resisted by the straps and by the clamp device. Owing to the fact that the tension is slightly within the circle defined by the pin 19, the outward pressure on the tub tends to pull the end 28 of the clamp toward the tub and therefore this pressure holds the clamp tight so that it cannot be released by this pressure. After the pomace has been fully pressed, the

screw is released and the head 4 may be removed. To release the pomace, which is now tightly held in the lower portion of the tub, the arm 25 of the clamp is swung out away from the tub and during this operation 70 the curved edges 26 rock against the stationary strap 16 and this relieves the clamp of any binding action against the tub; and the clamp is therefore easily released notwithstanding the great pressure which may be 75 exerted upon the strap. During this movement the point 23 moves to the left in Figure 3 and the point 19 moves to the right until the strap has been swung over to the full extent when the total length of the strap 17, 80 21 will be increased in extent equal to twice the distance between the pin 19 and the point 23. This permits the lower ends of the tub sections to swing apart thereby releasing the pomace contained in the tub which will 85 either drop out or it may be readily pushed out by hand. If the body of pomace has been forced into the spaces between the upright bars 6 the swinging apart of the tub sections in the manner set forth will readily 90 release the body of pomace notwithstanding that it is lying partly in the spaces 7.

The clamp is of very simple construction and may be stamped from sheet metal. It will be apparent that the clamp may be used in many other ways where two ends of a strap or cable are to be drawn toward each other for tightening and therefore I desire to be protected in all uses thereof.

Having described my invention, what I claim is:

1. A tub for cider presses comprising bars, strap members each connected with the bars of one section of the tub; pivotal connections between said strap members whereby separate sections of the tube may pivot from a line adjacent one end of the tub, the pivotal line extending transversely of the tub, a strap member attached to the bars adjacent the opposite end of one of the tub sections, a strap attached to the bars adjacent the end of the other tub section and having ends overlapping said last mentioned strap, and a clamp for drawing on said ends of the last mentioned strap to hold the tub sections in closed position.

2. A tub for cider presses comprising bars, strap members each connected with the bars of one section of the tub, pivotal connections between said strap members whereby separate sections of the tub may pivot from a line adjacent one end of the tub, the pivotal line extending transversely of the tub, a strap member attached to the bars adjacent the opposite end of one of the tub sections, a strap attached to the bars adjacent the end of the other tub section and having ends overlapping said last mentioned strap, and a clamp for drawing on said ends of the last mentioned strap to hold the tub

sections in closed position, said clamp being adapted to lie against said first mentioned strap.

3. A tub for cider presses comprising bars, 5 strap members each connected with the bars of one section of the tub, pivotal connections between said strap members whereby separate sections of the tub may pivot from a line adjacent one end of the tub, the pivotal line extending transversely of the tub, a strap member attached to the bars adjacent the opposite end of the tub for drawing the sections together in closed position, a clamp pivotally connected with the ends 15 of said last strap member and adapted to be swung to draw said strap sections toward each other, said clamp having a curved rocking edge for engaging the tub.

4. A clamp for drawing toward each 20 other the ends of straps, cables or the like, comprising a fork having a handle, a strap or the like having a pivotal connection, with the fork adjacent the point of bifurcation, a strap or the like having a pivotal connec-

tion with the outer ends of said fork, the 25 positions of said pivotal connections being such that when said handle is in closed position against one of said straps, the line of pull between said straps will resist the opening or releasing of said clamp. 20

5. A clamp for drawing toward each other the ends of straps, cables or the like, comprising a fork having a handle, a strap or the like, having a pivotal connection with the fork adjacent the point of bifurcation, 35 a strap or the like having a pivotal connection with the outer ends of said fork, the positions of said pivotal connections being such that when said handle is in closed position against one of said straps, the line of 40 pull between said straps will resist the opening or releasing of said clamp, said clamp having a curved rocking edge on which the clamp may have a rocking engagement with a surface when being opened. 45

Signed at the city, county and State of New York, this 11th day of April, 1924.

DANIEL E. REED.
